UNITED STATES PATENT OFFICE

138,453

DESIGN FOR A WASHBOARD

Aal Loomis, Santa Barbara, Calif.

Application April 17, 1944, Serial No. 113,274

Term of patent 7 years

(Cl. D49—1)

To all whom it may concern:

Be it known that I, Aal Loomis, a citizen of the United States, residing at Santa Barbara, in the county of Santa Barbara and State of California, have invented a new, original, and ornamental Design for a Washboard, of which the following is a specification, reference being had to the accompanying drawing, forming part thereof.

The figure is a perspective view of a washboard showing my new design. The back of the washboard is substantially plain.

I claim:

The ornamental design for a washboard, as shown and described.

AAL LOOMIS.
